CONVEYER CANVAS

Joseph E. Novak, Berwyn, Ill.

Application June 11, 1938, Serial No. 213,207

5 Claims. (Cl. 198—199)

The present invention relates to a conveyer canvas, such as the adjuster, elevator and platform canvas for different types of binders, headers and combines. The invention is directed more particularly to a canvas having conveyer mechanism secured to the canvas belt by means of metal staples or the like which are driven through the canvas, through slots in tubular metal cross bars and through fillers in said cross bars, and finally through the metal forming the outer faces thereof, against which the projecting ends of the staples or fastening means are bent or clamped.

It is an object of this invention to provide a conveyer canvas having filled metal conveyer cross bars or slats which are secured to the canvas by means of staples which are driven through the canvas, through the fillings and through the outer metal faces of the cross bars or slats.

It is also an object of this invention to provide a conveyer canvas having filled metal cross bars or slats which are rigidly secured to the canvas by means of staples which project through the canvas and through the metal outer faces of the cross bars or slats to produce a construction wherein the filled metal cross slats are rigidly secured to the canvas without danger of them pulling off, as they do in earlier types of conveyer canvases, wherein the staples project through the canvas and only into the filling material of the cross bars or slats.

An important object of this invention is to provide an improved and simplified form of conveyer canvas wherein the filled metal cross bars or slats which form the conveyer mechanism are rigidly secured to the canvas by means of staples which project through the canvas, through the cross bar fillings and through the metal forming the cross bars, with the ends of the staples or fastening means being tightly crimped over and clamped against the outer faces of the metal cross bars.

Other and further important objects of this invention will be apparent from the disclosures in the specification and the accompanying drawing.

The invention (in a preferred form) is illustrated in the drawing and hereinafter more fully described.

On the drawing:

Figure 1 illustrates a fragmentary isometric view of a conveyer canvas provided with filled metal cross bars or slats secured in place by fastening means projecting through the canvas and through the filled metal cross bars.

Figure 2 is an enlarged fragmentary top plan view of a portion of the conveyer canvas illustrating the ends of the fastening means projecting through the metal cross bar and then bent over against the outer face thereof.

Figure 3 is an enlarged end view of one of the conveyer canvas cross bars associated with a fragmentary portion of the conveyer canvas belt.

Figure 4 is a fragmentary detailed cross section taken along one side of the fastening means of 10 the cross bar or slat shown in Figure 3.

Figure 5 is a longitudinal vertical detailed section taken on the line V—V of Figure 4.

As shown on the drawing:

The reference numeral 1 indicates a strip of 15 canvas or other suitable flexible material of a predetermined width and length adapted to have the end portions thereof connected by any suitable type of connecting means to form a continuous conveyer belt.

The conveyer canvas is provided at predetermined spaced intervals with transversely disposed conveyer slat mechanisms, each of which comprises a substantially rectangular cross-sectioned hollow metal tube or cross bar 2 including 25 a closed top 3 and a bottom 4 provided with a longitudinal slot 5 extending throughout the length of the cross bar or slat. Each of the metal cross bars or slats 2 is filled with a composition 30 filler 6, such as rubber, asphalt or any other suitable filling material which may serve the purpose.

The improved type of filled metal cross bars or slats are secured in place transversely across the outer face of the conveyer canvas belt 1 by means of an improved type of machine which not only 35 cuts the staples but punches the staples through the canvas, the filling material of the cross slats, and the metal shells of said cross slats, and finally bends over and clinches the projecting ends of the staples tightly against the outer faces 40 of the metal walls 3 of the cross slats 2.

As clearly illustrated in Figures 4 and 5, the filled metal cross slats 2 are secured to the canvas 1 by means of the U-shaped staples 7, the arms of which project through the canvas, through 45 the slots 5 of the metal cross slats, through the filling material 6 of the slats, and finally through punched openings in the outer or top walls 3 of the cross slats to rigidly hold the cross slats and canvas secured together by clinching over the 50 ends 8 of the staples to clamp tightly against the top walls 3, thereby producing a construction which rigidly holds the filled metal slats to the canvas without danger of the staples or fastenings pulling out. A construction is therefore pro- 55

vided which obviates the defects in other types of conveyer canvases wherein staples are only driven through the canvas and into the filling material of the cross slats.

5 It will, of course, be understood that numerous details of construction may be varied through a wide range without departing from the principles of this invention, and it is therefore not the purpose to limit the patent granted hereon otherwise than necessitated by the scope of the appended claims.

I claim as my invention:

1. In a binder canvas mechanism including a canvas strip, filled metal cross slats mounted transversely across the outer face of the canvas strip at spaced intervals, and fastening staples projecting through the canvas and through the filled metal cross slats, with the ends of said staples bent over and tightly clamped against the outer faces of the metal cross slats.

15 2. In a binder canvas mechanism including a canvas belt, slotted hollow cross slats positioned transversely across the outer face of the canvas belt, composition fillers disposed within the hollow metal cross slats, and fastening staples projecting through the canvas belt, through the cross slats and the fillers, and through the metal outer walls of the cross slats, with the ends of said fastening staples bent over and crimped tightly against the outer faces of said cross slats.

20 3. A conveyer canvas structure including in

combination a longitudinally slotted metal cross slat having a filler therein, and fastening means punched through the canvas, the filler and through the metal walls of the cross slat.

5 4. In a binder canvas mechanism including a canvas belt, a plurality of spaced tubular metal cross slats having slots therein, said slotted cross slats having the slotted portions thereof positioned against the outer face of the canvas belt, plastic fillers engaged in the slotted cross slats, and staple fasteners punched through the canvas belt, through the fillers in the cross slats, and through the walls of the metal cross slats, with the ends of the staple fasteners crimped tightly against the exterior of the metal cross slats.

10 5. In a binder canvas belt structure including a canvas belt, an elongated metal slat disposed on said belt and extending transversely thereof, said slat being formed of a piece of metal bent to define a substantially rectangular casing with the free ends thereof disposed in spaced opposed relation to define a longitudinal slot bounded by spaced aligned lips, a plastic filler in said casing, and staple fasteners punched through the belt and through said filler and through a wall of the casing to draw a portion of the belt into said slot and against said lips, and having their ends crimped tightly against the exterior face of a wall of said casing.

15 JOSEPH E. NOVAK. 30
